(57) **CLAIM**

The ornamental design for a carrier for a conveyor system as shown and described.

DESCRIPTION

FIG. 1 is a perspective view of a carrier for a conveyor system showing our new design;

FIG. 2 is a front view thereof;

FIG. 3 is a rear view thereof;

FIG. 4 is a top view thereof;

FIG. 5 is a bottom view thereof;

FIG. 6 is a right side view thereof;

FIG. 7 is a left side view thereof; and,

FIG. 8 is an enlarged cross-sectional view taken along lines 8-8 shown in FIG. 2.

The broken lines in the drawings are for the purpose of illustrating portions of the carrier for a conveyor system that form no part of the claimed design.

The dash-dot broken lines define the bounds of the claimed design and form no part thereof.
